UNITED STATES PATENT OFFICE.

FRANCIS J. McBRIEN, OF BROOKLYN, NEW YORK.

CLOTHES-CLAMP.

SPECIFICATION forming part of Letters Patent No. 292,243, dated January 22, 1884.

Application filed May 2, 1883. (No model.)

To all whom it may concern:

Be it known that I, FRANCIS J. McBRIEN, a citizen of the United States, residing at Brooklyn, in the county of Kings and State of New York, have invented a certain new and Improved Clothes-Clamp for Beds, of which the following is a full, clear, and exact description.

This invention relates to a clamping device adapted to be applied to beds, cribs, cradles, and like articles for the purpose of holding the bed clothing or covering in place, the object being to prevent an invalid, child, or restless person from displacing or throwing off the covers, and also serving to hold the covers so firmly in place that they will tend to prevent the occupant from falling out of the bed.

My invention consists in the combination of a frame having one end adapted to fit over the side-board of a bedstead, for instance, and having its other end elongated to form a stationary jaw, and a movable jaw fulcrumed or pivotally connected near its center to the stationary jaw, said movable jaw being adapted to be moved toward and held firmly against said stationary jaw, or retracted from said stationary jaw, by means of a cam pivotally connected to said movable jaw, all as hereinafter fully set forth.

In the accompanying drawings, in which like parts are designated by similar letters of reference, Figure 1 is a side view of part of a bedstead with my improved clamping device applied thereto. Fig. 2 is a side view, in elevation, of my improved clamping device.

a designates the frame of my clamping device, having a square-cut opening in one end and two prongs or lips, *b b*. The other end of the frame *a* is elongated to form a stationary jaw, *c*, to which is fulcrumed or pivotally connected at *d* a movable jaw, *e*. As shown in Figs. 1 and 2, this movable jaw *e* is adapted to be moved toward and held firmly against said stationary jaw, or retracted therefrom by means of a cam, *f*, which is pivotally connected to the

inner end of the jaw *e*, and is capable of having an oscillating or partial rotary movement. Said cam *f* is provided with a thumb-piece, *g*, by which it may be operated. *h* designates a screw arranged to work in a screw-threaded opening in one of the prongs or lips *b*. The outer end of the screw *h* is provided with a thumb-piece, *i*, and *j* designates a buffer, of soft material, attached to its inner end, and adapted to prevent the screw *h* injuring or defacing the parts with which it may be brought in contact.

The attachment and operation are as follows, viz: The frame being set over the side-board of a bedstead, for example, as shown in Fig. 1, the side-board entering the opening and being straddled by the prongs or lips, the screw *h* is adjusted to bear against said side-board until the device is firmly held in place. The handle or thumb-piece *g* of the cam *f* is then raised, thereby carrying the jaw *e* out of contact with the jaw *c*, and the bed clothing or covers may then be inserted between the jaws and the jaws firmly clamped or locked together by bringing the cam into the position shown in Fig. 2, whereby the bed clothing or covering will be firmly held in place, as stated.

What I claim as my invention, and desire to secure by Letters Patent, is—

As a new article of manufacture, a clamping device consisting of a frame, *a*, having prongs or lips *b b*, and an adjustable screw, *i*, a stationary jaw, *c*, and a movable jaw, *e*, fulcrumed or pivotally connected to said stationary jaw and provided with the cam *f*, by means of which said jaw may be moved toward the clothing and hold the same in place at will, substantially as set forth.

In testimony whereof I have hereunto set my hand this 13th day of April, A. D. 1883.

FRANCIS J. McBRIEN.
